UNITED STATES PATENT OFFICE.

JOHN C. KAMAS, OF BELLVILLE, TEXAS.

STOCK BARRIER AND CROSSING.

Application filed August 13, 1927. Serial No. 212,753.

This invention relates to stock barriers, and its general object is to provide a combined stock barrier and rack crossing adapted to bridge ditches, run-ways, streams and the like.

The general object of the invention is to provide a device of the character above set forth, that will prevent stock from straying from a pasture, yet provides a crossing that can be used for motor vehicles, and is capable of being arranged for horse drawn vehicles.

Another object of the invention is to provide a stock barrier and bridge for ditches and the like, that is simple in construction, inexpensive to manufacture, strong and durable and efficient in operation and service.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a front view of the device forming the subject matter of the present invention and showing the same in applied and open position.

Figure 2 is a top plan view of the device in open position.

Figure 3 is a similar view in closed position.

Figure 4 is a sectional view taken on line 4-4 of Figure 2 looking in the direction of the arrows.

Figure 5 is a sectional view taken on line 5-5 of Figure 2 looking in the direction of the arrows.

Figure 6 is a fragmentary sectional view taken approximately on line 6-6 and looking in the direction of the arrows.

Referring to the drawings in detail, the letter A indicates a ditch, B fence posts and C the wire of a fence which terminates with the post for providing a gate opening as will be apparent and as shown in Figure 1.

While I have disclosed my device as bridging a ditch, it will be obvious that it can be used in the place of an ordinary gate as in any event it will prevent cattle and the like from straying from the pastures separated by the fence as shown.

The device includes base supports 1 which as shown are supported upon the opposite banks thereof. Arranged in parallelism with their ends disposed upon the base supports 1, are a plurality of cross pieces 2 which have fixed thereon parallel bars 3 arranged at right angles thereto as best shown in Figure 2 of the drawings. Secured to the opposite ends of the cross pieces 2 are strips 4 which are disposed in superposed relation with respect to the base supports and arranged between the base supports and strips are cover planks 5.

The parallel bars 3 are disposed in equidistantly spaced relation with respect to each other and are so spaced to an extent sufficient to prevent cattle from attempting to cross the same, but are sufficiently close together to allow motor vehicles to cross as will be apparent.

In order to allow cattle to cross and also to provide a crossing which may be used by horse drawn vehicles, I provide a sectional rack which cooperates with the parallel bars 70 in a manner which will be presently apparent.

Arranged adjacent the ends of the strips 4 are strip hinges 6 which are of the usual U-shaped configuration and terminate in apertured ears 7 through which pass suitable securing means for fixing the hinges to the strips as above set forth and as clearly shown in Figure 2 of the drawings. Each section of the rack includes side members 8 and 9, and the side members 8 are substantially semi-circular in cross section and have their ends mounted in the strap hinges 6, and in order to prevent longitudinal movement of the side members 8 in said hinges, I provide right angle shape strips 10 which are fixed to the strips 4 and have one of their portions engaging the ends of the side members 8 as best shown in Figure 5 of the drawings. The side members 9 are substantially rectangular in cross section and have their ends recessed 90 as at 11 to provide handles for lifting the racks from their closed position as shown in Figure 3, to their open position as shown in Figure 2. The sections of the rack also include spaced parallel bars 12 which are secured to said side members 8 and 9 in a manner whereby they will be arranged between the bars 3 when the sections are disposed in closed position, and bridging the end bars 12 are converging braces 13.

From the above description and disclosure of the drawings, it will be obvious that I

have provided a combined barrier and bridge adapted to be arranged across a ditch, runway, stream or the like or can be disposed in a gate-way, so as to prevent cattle from crossing the same, but when it is desired that the cattle should cross or to use the same for horse drawn vehicles, the sections of the rack are lowered so that the bars 12 cooperate with the bars 3 and provide a relatively smooth crossing surface as will be apparent.

In order to retain the sections of the rack in their raised position as best shown in Figure 4, I may provide a hook which may be pivotally secured to the fence posts B and are adapted to receive the side members 9.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

25 A barrier and crossing of the character de-

scribed comprising a pair of base supports, cross pieces bridging the base supports and having their ends secured thereto, parallel bars secured in spaced relation with respect to each other and to said cross pieces, strips secured to the ends of said cross pieces and in parallelism with said bars, a sectional rack, side members included in said sectional rack, one side member of each section being substantially semi-circular in cross section and being hingedly secured adjacent the ends of said strips, angle plates secured to the strips and being engageable with the ends of the semi-circular in cross section side members to prevent longitudinal movement thereof, the other side members having reduced ends engageable with the strips, bars secured to said side members in spaced relation and arranged thereon in a manner whereby they will be disposed between the bars first mentioned when the sections are arranged in one position and converging braces bridging some of the bars.

In testimony whereof I affix my signature
JOHN C. KAMAS.
